SAMUEL J. LUPTON AND FRANCIS E. COLLINSON, OF WINNIPEG, MANITOBA, CANADA.

WATER CIRCULATOR FOR BOILERS.

Application filed February 16, 1926. Serial No. 88,694.

Our invention relates to locomotive boilers and has particular reference to apparatus for introducing feed water thereto which will improve the circulation within the 5 boiler.

In boilers of the locomotive type in which the portion of the boiler outside the fire box comprises a cylindrical shell substantially filled below the water line with a plurality of horizontal fire tubes, the water circulation in the lower portion of the boiler and at the forward end is notoriously sluggish. This condition is due to the fact that the lowermost rows of tubes transmit a relatively small amount of heat to the water in the boiler, and also to the presence of a considerable layer of water below the level of the lowermost tubes, to which insufficient heat is transmitted to cause it to rise and mingle with the rest of the water in the 20 boiler.

The existence of this comparatively stagnant body of water in the bottom of the boiler materially reduces the steaming capacity of the boiler below that which can be secured with an efficient circulation of water throughout the boiler, and the principal object of the present invention is to improve the boiler circulation and thereby increase 25 the evaporating capacity and efficiency of the boiler. Further and more detailed objects of the invention and the manner of their accomplishment will appear more fully in the following detailed description 30 of a preferred embodiment of the invention, illustrated in the accompanying drawings, in which Fig. 1 is a fragmentary longitudinal section of the forward portion of a locomotive boiler to which our invention has been applied, certain parts being shown in 35 elevation. Fig. 2 is a transverse section of the boiler taken on the line 2—2 of Figure 1, and Figure 3 is a fragmentary section on an enlarged scale, taken along the line 40 3—3 of Figure 1.

Referring now to the drawings, the main boiler shell is indicated at 1, with the forward end of the boiler being formed by the usual flue sheet 2, to which are suitably secured the fire tubes 3 and the large flues 4, the latter being adapted to receive superheater units (not shown). A cylindrical sheet 5, attached to the forward end of the main boiler shell, forms the usual boiler 45 smoke box.

In boilers of this description, the feed

water, which may or may not be preheated, is delivered either by means of a feed pump or an injector through a feed pipe 6, usually entering the boiler at substantially its horizontal mid-section. As may readily be seen from an inspection of Figure 2, feed water fed to the boiler in this manner, whether it be cold or preheated, has substantially no effect upon the water circulation (or lack of it) in the bottom of the boiler, and by our present invention we propose to utilize the feed water, which, in locomotive service is being substantially continuously supplied to the boiler, to promote a better circulation 70 therein.

In order to accomplish this object the usual boiler feed pipe 6 is brought forward of the flue sheet of the boiler, through the smoke box sheet 5, and is extended by means 75 of a pipe 7 to connect with a fitting 8 which provides a passage for the feed water to the boiler. The fitting 8 is preferably located centrally of the boiler to extend through an opening 9 at the lowest point of flue sheet 2, the pipe 7 being curved to substantially conform to the periphery of the sheet 5 in order to leave the locomotive smoke box unobstructed for access to the flue sheet. A second curved pipe 10, substantially conforming to the periphery of the smoke box 80 wall, connects an opening 11 in the flue sheet 2 immediately below the normal water level 85 of the boiler, with the fitting 8.

The fitting 8, as illustrated in Fig. 3, comprises a T shaped member, preferably an integral casting, forming an outer nozzle 12, and an inner nozzle 13, located concentrically within the outer nozzle 12, and terminating at a point within the latter. The 90 flanged end 14, of the fitting forms a passage at right angles to the nozzle 12 and connected therewith, while the oppositely disposed end 15 of the fitting forms an inlet 95 passage for the nozzle 13 and the nozzle end 100 of the fitting 8 is provided with an external flange 16, by which the fitting is suitably secured to the flue sheet, as by studs 17. A tight joint is secured between the flue sheet and the fitting by means of a suitable packing ring 18. The end 15 of fitting 8 is 105 suitably connected to the pipe 7 and the pipe 10 is connected to the end 14 of the fitting.

The operation and advantages of the device will be apparent to those skilled in the 110 art, and may be briefly summarized as follows: Feed water entering the boiler

through the nozzle 13 produces an ejecting action within the nozzle 12 which results in drawing hot water from the upper portion of the boiler downwardly through the pipe 10 5 to be mingled with the incoming feed water and forced into the boiler rearwardly along the bottom of the boiler shell. This action obviously results in an improved circulation by replacing comparatively cool water in 10 the boiler with heated water taken from the upper portion of the boiler. The comparatively hot water, centrally introduced into the front end of the bottom of the boiler, tends to rise, thereby setting up a circulation, 15 as this rising column of water is replaced not only by the incoming feed water mingled with more hot water from pipe 10 but also by water which tends to flow downwardly from the lower side portions of 20 the boiler.

Furthermore, scaling conditions within the boiler are improved by the application of this apparatus. Feed water, even when preheated, is not brought to a temperature 25 which will precipitate most of the solids therein, such precipitation usually occurring at or near the point of entry of the feed water into the boiler. With the usual location of feed water inlet—that is, near the 30 upper part of the tube bank at the forward end of the boiler—the incoming feed water has precipitated from it quantities of scale-forming matter which adheres and forms a hard scale deposit on the upper rows of fire tubes near their forward end. This scale forms an obstruction to the forward circulation of water along the top of the boiler and materially reduces the effective evaporating capacity of the forward portion of 40 the tubes. With the arrangement presented by our invention, this undesirable condition is eliminated and the feed water is injected into the boiler at a point where the deposit of scale-forming matter will least affect 45 the steaming properties of the boiler. Furthermore, impurities deposited on the bottom sheet of the boiler, which is comparatively cool, remain in the form of a soft sludge, instead of baking into a hard scale, 50 and may be readily removed by proper blowoff apparatus.

In addition, the mixing of the feed water with water at boiler temperature materially raises the temperature of the water entering the boiler and this, together with the circulation which is set up by the incoming stream, assists in equalizing the water tem-

perature throughout the boiler and thereby materially reduces the strains in the latter set up by the existence of unequal temperatures.

What we claim is:

1. In a locomotive, the combination with a firetube boiler; of a conduit leading from a point below and adjacent the normal boiler 65 water level and terminating in a rearwardly directed opening adjacent the bottom of the forward end of the boiler, and a feed water supply pipe terminating within said conduit in a discharge end directed toward the lower end of said conduit.

2. In a locomotive, the combination with a horizontal firetube boiler having a forward tube sheet; of a conduit connecting an opening in said sheet below and adjacent the normal boiler water level with an opening adjacent the bottom of said sheet, and a feed water supply pipe terminating within said conduit in a discharge end directed toward 75 the lower end of said conduit.

3. In a locomotive, the combination with a boiler having a plurality of horizontal firetubes connected to a forward tube sheet, and a smokebox extending forwardly of said sheet; of a conduit connecting an opening 85 in said sheet below and adjacent the normal boiler water level with an opening in said sheet below the lowermost of said tubes, said conduit lying adjacent the periphery of said smokebox, and a feed water supply 90 pipe passing through said smokebox wall and terminating within said conduit in a discharge end directed toward the lower end of said conduit.

4. In a locomotive, the combination with 95 a boiler comprising a forward tube sheet, a plurality of horizontal fire tubes connected thereto, said sheet having an opening located adjacent the periphery thereof above said tubes and below the normal boiler water 100 level, and a second opening located centrally below said tubes, of a fitting attached to said flue sheet and comprising an outer nozzle extending rearwardly through said second opening, and a rearwardly directed inner nozzle terminating within the outer nozzle and spaced therefrom; a pipe connecting 105 said first named opening with the outer nozzle, said pipe lying substantially at the circumference of said sheet, and a feed water supply pipe connected to the inner nozzle.
